2,776,600

SEAR DEVICE FOR AN AUTOMATIC FIREARM

Edward C. Lee, Detroit, Mich., assignor to the United States of America as represented by the Secretary of the Army

Application December 31, 1953, Serial No. 401,741

3 Claims. (Cl. 89—136)

This invention relates to automatic firearms wherein a firing member is resiliently mounted for slidable movement in a reciprocating bolt and is particularly directed to means for securing the firing member in a cocked position and for the release thereof when the bolt is in a battery position.

In automatic firearms of the type described in Patent No. 1,628,226 to John M. Browning, there is provided a longitudinally reciprocating bolt having a spring-biased firing member mounted for slidable movement between a forward firing position and a rearward cocked position. The firing member is arranged to be releasably retained in the cocked position by a spring-biased sear reciprocably mounted in vertical slideways. When the bolt is moved to the battery position, the sear is actuated by suitable means to release the firing member which moves forwardly under the bias of its spring to discharge the chambered cartridge. During the ensuing recoil movement of the bolt, a cocking lever pivotally mounted therein, moves the firing member rearwardly ready for engagement with the sear. During counter-recoil of the bolt, the cocking lever is counter-rotated permitting the firing member to be biased slightly forward into releasable engagement with the sear and the bottom end of such cocking lever is swung free of the firing member whereupon the latter is free to move forwardly when released by the sear to effect another cycle of operation.

In firing mechanisms of this type, considerable trouble has been experienced with the sear prematurely releasing the firing member whereby the chambered cartridge is not fired because the firing member does not strike the primer with sufficient force to ignite it.

The conventional type sear is maintained in holding position only by the bias of its spring and there are no means provided to prevent the sear from vibrating through the shocks produced during operation of the firearm. Consequently, vibration of the sear while engaging the firing member causes either faulty or mis-engagement and vibration during engagement causes the firing member to be prematurely released.

Accordingly, it is an object of this invention to provide in an automatic firearm a sear mechanism which holds the firing member in positive engagement until actuated by a sear slide.

A further object of this invention is to provide in an automatic firearm bolt a pivotally mounted sear which reciprocates smoothly between a firing member holding position and a disengaged position.

It is the specific object of this invention to provide in an automatic firearm bolt a slidably mounted sear slide which both locks the sear in the firing member holding position and actuates the sear to disengaged position.

The specific nature of the invention as well as other objects and advantages thereof will clearly appear from a description of a preferred embodiment as shown in the accompanying drawings in which:

Fig. 1 is a longitudinal cross-sectional view of a firearm bolt showing the firing member in retracted position;

2

Fig. 2 is a fragmentary view similar to Fig. 1 but showing the firing member in the fire position;

Fig. 3 is an end view of the bolt partially cross-sectioned to show the mounting of the sear slide and sear slide actuator;

Fig. 4 is an enlarged exploded view of the sear mechanism;

Fig. 5 is an enlarged fragmentary perspective view of the sear slide showing the sear actuating cam surfaces;

Fig. 6 is a view taken along line 6—6 of Fig. 1 showing the sear in locked firing member holding position;

Fig. 7 is a view similar to Fig. 6 but showing the sear unlocked and initially contacted by the sear slide for rotation thereof; and

Fig. 8 is a view taken along line 8—8 of Fig. 2 showing the sear actuated to firing member disengaged position.

Shown in the figures is a bolt 12 of the well-known Browning type in which there is provided a longitudinal

20 channel 13 and a forwardly extending bore 14 and counterbore 15. A sear 16 of bell crank configuration is mounted in channel 13 as hereinafter described for pivotal movement between a holding position and a disengaged position. Mounted for slidable movement in bore 14 and counterbore 15 is a firing member 17 which is reciprocable

25 between a firing and a retracted position. Firing member 17 is essentially of conventional type, being provided with a striker portion 18, a hollow extension portion 19, which houses a compressible spring 20, and a forwardly facing hook portion 21 which projects downwardly from a slabbed portion 22 located at the rear end of such extension portion. In addition, there is provided a tongue portion 23 which extends rearwardly from hook

21.

30

35

Provided in the upper side of bolt 12 is a recess 24 which communicates with counterbore 15 by means of a vertical slot 25. Mounted in recess 24 is a cocking lever stop member 26 having a pin portion 27 which extends downwardly through a hole 28 to be received by an elongated slot 29 in extension 19. The rear end of spring 20 is arranged to bear against pin 27 whereby firing member 17 is biased to the firing position.

40

45

A cocking lever 30 is mounted in slot 25 on a transverse pin 31. The end of cocking lever 30, extending below pin 31, is receivable by slot 29 and is arranged to be engageable with the rear end thereof. The upper end of cocking lever 30 is receivable in a V-slot 32 provided in a top plate bracket 34 of the firearm during initial recoil and is slidably engageable thereafter with the underside of the top plate bracket during the remainder of the recoil. Thereby, cocking lever 30 is pivoted in clockwise direction to actuate firing member 17 against the bias of spring 20 to the retracted position and holds the

50

55

firing member in such retracted position until pivoted in counter-clockwise direction. During counter-recoil of bolt 12, the top end of cocking lever 30 reengages with V-slot 32 whereby such cocking lever is pivoted in counter-clockwise direction, permitting firing member 17 to be biased by spring 20 slightly forward for cocked engagement with sear 16, as hereinafter described, and the bottom end swung free of slot 29.

<

ranged to receive tongue 23 when firing member 17 is in the retracted and cocked positions and the top side of foot portion 35, forwardly of engaging surface 39, is arranged to be slidably engaged with the underside of tongue 23 when firing member 17 reciprocates between cocked and firing positions. Provided in the bottom side of channel 13 is a well 40 which receives one end of a compressible spring 41. The opposite end of spring 41 bears against the bottom side of foot portion 35 whereby sear 16 is biased to the holding position.

Located laterally through the upper portion of leg 36 is a cylindrical bore 42 having an upwardly extending opening formed by a front and rear laterally arranged lip portion, noted by 44 and 45 respectively. Projecting forwardly and outwardly from front lip 44 and the adjoining portion of bore 42, as best shown in Fig. 4, are similar right and left vertical cam surfaces, noted by 47 and 48 respectively.

Provided laterally through bolt 12 is a cylindrical bore 50 arranged to intersect the upper portion of channel 19. A cylindrical sear slide 51 is reversibly mounted for slideable movement in bore 50 and is adapted to cooperate with lug 46 and cam surfaces 47 and 48, as hereinafter described. Sear slide 51 is recessed, as noted by 52 and best shown in Fig. 5, so as to form spaced apart angular actuating surfaces 53 and similar actuating surfaces 54 angularly related thereto. Provided in sear slide 51, opposite recess 52, is a mortise 61. Recess 52 and mortise 61 are located in sear slide 51 away from the longitudinal center thereof so as to establish a long portion 55, which is engageable by a trigger mechanism (not shown) when installed in either the right or the left side of bolt 12, and a short portion 56. When sear slide 51 is assembled for operation from the right side of bolt 12, actuating surfaces 53 are arranged to cooperate with cam surfaces 47 and 48 and when assembled for operation from the left side, actuating surfaces 54 cooperate with such cam surfaces. Sear slide 51 is secured against rotation by sear slide actuator 62 which is slidably mounted in a vertically disposed cylindrical hole 71 to transverse the sear slide as hereinafter described. A cup-like member 57 is installable in bore 50 so as to be adjacent short portion 56 and is secured in position by a pin 58 which is receivable by one of a pair of opposed holes 59 provided therein. A spring 60 is received by member 57 and is arranged to bear against the end of short portion 56 to bias sear slide 51 away to a sear locking position.

When assembled in bolt 12 for operation from the right side, sear slide 51 is biased by spring 60 so that the left one of the actuating surfaces 53 engages with cam surface 48. At the same time, lug 46 is engageable with the cylindrical surface of sear slide 51 whereby sear 16 is blocked against pivoting from holding position. To actuate sear 16 from holding to disengaged position, long portion 55 is pressed inwardly. At the point where the right one of actuating surfaces 53 engages the mating cam surface 47, mortise 61 is moved adjacent lug 46, unblocking sear 16. Consequently, when further movement of actuating surface 53 against cam surfaces 47 moves the top side of leg portion 36 forwardly, pivoting foot portion 35 downwardly to disengage firing member 17, lug 46 is received by mortise 61. When sear slide 51 is assembled for operation from the left side of bolt 12, the right one of actuating surfaces 54 is biased into normal engagement with the mating cam surface 47 and the camming engagement of the left one of actuating surfaces 54 with the mating cam surface 47 moves the unblocked sear 16 to disengaged position.

As has hereinbefore been recited, sear slide 51 is transversed by sear slide actuator 62 which secures the sear slide against rotation and is also the means of actuating sear 16 from the top side of bolt 12. Sear slide actuator 62 is comprised of a cylindrical portion 65 from which there extends downwardly a portion 66 substantially of

elongated rectangular cross section. Intermediate one of the narrow sides of portion 66 is a ramp 67 which inclines downwardly and inwardly to form an extending guide portion 68 of smaller dimension. Guide 68 is slidably received in a suitable opening below bore 50.

An elongated hole 69 is provided in sear slide 51 on each side of recess 52, one of which is arranged to slidably receive portion 66 of sear slide actuator 62 whether sear slide 51 is assembled from the right or left side of bolt 12. 10 Provided in each hole 69 is an angular side 70 engageable by ramp 67 whereby sear slide 51 is cammable to actuate sear 16 when a vertical force is applied to sear slide actuator 62. It has been brought out that when reversed in bolt 12, sear slide 51 also has to be rotated 180° to have the opposite ones of actuating surfaces 53 or 54 cooperable with the cam surfaces 47 and 48. Consequently, angular side 70 has to be located oppositely in the holes 69 making it necessary for sear slide actuator 62 to be rotated to have ramp 67 engageable therewith. 15 Provided in cylindrical portion 65 is a pair of grooves 75, one of which is engageable with an arm portion 76 of clocking lever stop member 26 to limit the movement of sear slide actuator 62 in whichever position sear slide actuator 62 is installed.

20 To assemble sear 16 in bolt 12, the sear is placed in channel 13 and sear slide 51 then assembled through bolt 12, transversing sear 16 through bore 42. Sear 16 is then depressed against spring 41 until the mounting pin 37 can be assembled through hole 33 whereby sear slide 25 51 is properly positioned between lips 44 and 45.

When a firearm incorporating the sear mechanism of this invention is to be fired, a trigger mechanism (not shown) either presses downwardly on sear slide actuator 62, which actuates sear slide 51 by the camming engagement of ramp 67 thereon with the mating angular side 70 in the sear slide, or inwardly on the end of long portion 55 of sear slide 51 if operation from the side of the firearm is desired.

If the sear mechanism is arranged for operation from 40 the right side of the firearm, the left one of actuating surfaces 53 in sear slide 51 is in resilient engagement with cam surfaces 48 in sear 16 when the firearm is in battery. When the trigger mechanism (not shown) presses sear slide 51 inwardly to fire the firearm, the initial movement of the sear slide moves mortise 61 in position to receive lug 46 and then engages the right one of actuating surfaces 53 with the mating cam surface 47. Continued movement of sear slide 51 causes leg portion 36 of sear 16 to be moved forwardly by the camming engagement of 45 actuating surface 53 with cam surface 47. As sear 16 is bell crank in configuration and operation, the forward movement of leg portion 36 moves foot portion 35 downwardly causing engaging surface 39 to move out of engagement with hook 21 of firing member 17 which is then free to be urged forwardly by its spring 20 to fire the chambered cartridge. During the forward travel of firing member 17, the bottom sides of hook 21 and tongue 23 slidably engage the top side of foot portion 35 forwardly of engaging surface 39, thereby holding sear 16 50 in the disengaged position.

During the ensuing recoil of bolt 12, the top end of cocking lever 30 is received by V-slot 32 causing the lower end to engage the end of slot 29 in extension 19 for actuation of firing member 17 to retracted position. Firing member 17 is maintained in retracted position during the remainder of the recoil by the engagement of the top end of cocking lever 30 with the bottom side of top plate bracket 34. When hook 21 is moved rearwardly of engaging surface 39, sear 16 is free to be biased to holding position by spring 41 with the hook 21 and tongue portion 23 being received by indent 38. As sear 16 moves to holding position, cam surface 47 is moved forwardly permitting sear slide 51 to be biased by spring 60 to lock position wherein sear 16 is blocked against movement 55 from holding position by the engagement of the surface

of sear slide 51 with lug 46. During counter-recoil of bolt 12, the top side of cocking lever 30 is again received by V-slot 32 causing the cocking lever to pivot and thereby permit firing member 17 to be biased forwardly by spring 20 until stopped in cocked position by the engagement of hook 21 with the engaging surface 39. During the impact of engagement and the remainder of the travel of bolt 12 to battery, sear 16 is blocked against movement away from holding position, by the means already explained, and thereby there is prevented any chances of 10 firing member 17 being prematurely released.

It is readily apparent from the foregoing that there is here provided a superior sear mechanism of sturdy, easily fabricated construction in which the sear moves smoothly between a holding and a disengaged position and securely 15 holds the firing member against premature release.

Although a particularly embodiment of the invention has been described in detail herein, it is evident that many variations may be devised within the spirit and scope thereof and the following claims are intended to include such variations.

I claim:

1. In a firearm bolt, a sear having a leg portion and a foot portion extending at right angles therefrom, said leg portion being provided with a lateral opening and said foot portion being provided with a rearwardly facing engaging surface in the upper side thereof, pin means mounted through said sear to provide for pivotal movement of said sear about the junction of said leg portion and said foot portion, spring means for biasing said sear from a disengaged to a holding position, a cam portion extending rearwardly into said opening, a lug portion extending forwardly into said opening, a reciprocal firing member spring-biased from a retracted to a firing position, hook means extending from said firing member, said hook means being engageable by said engaging surface when said sear is in said holding position whereby said firing member is releasably held in said retracted position, a cylindrical sear slide slidably mounted in a bore in the bolt for reception by said opening, said sear slide being provided with a mortise and a recess having angular actuating surfaces, said sear slide being actuatable from a sear actuated position to a sear locked position wherein said lug is engageable with said sear slide to block said sear in said holding position, and said actuating surfaces being cooperable with said cam portion for actuating said sear to said disengaged position when said sear slide is moved to said sear actuated position and said mortise is in position to receive said lug.

2. In a firearm bolt, a sear having a leg portion and a foot portion extending at right angles therefrom, said leg portion being provided with a lateral opening and said foot portion being provided with a rearwardly facing engaging surface in the upper side thereof, pin means mounted through said sear to provide for pivotal movement of said sear about the junction of said leg portion and said foot portion, spring means for biasing said sear from a disengaged to a holding position, a cam portion extending rearwardly into said opening, a lug portion extending forwardly into said opening, a reciprocal firing member spring-biased from a retracted to a firing position, hook means extending from said firing member, said hook means being engageable by said engaging surface when said sear is in said holding position

5 whereby said firing member is releasably held in said retracted position, a spring-biased cylindrical sear slide slidably mounted in a bore in the bolt for reciprocation in said opening between a sear locked position and a sear actuated position and being normally engageable by said lug whereby said sear is blocked in said holding position, said sear slide being provided with a recess having angular end walls cooperable with said cam portion for actuation of said sear to said disengaged position, a hole on each side of said recess and a mortise for receiving said lug when said sear slide is away from said sear locked position whereby said sear is pivoted to said disengaged position, angular sides in said holes, and a cylindrical actuator member slidably received in either one of said holes for securing said sear slide against rotation, said actuator being provided with a ramp portion selectively cooperable with said angular sides whereby a vertical force applied against said actuator member is translated to lateral movement of said sear slide.

3. In a reciprocating firearm bolt, a reciprocable firing member spring-biased from a retracted to a firing position, lever means for retracting said firing member responsive to recoil of the bolt, a sear of bell crank configuration pivotally mounted on a centrally transversing pin, cooperating latch means on one arm of said sear and said firing member for releasably latching said firing member in said retracted position, a lip on the other arm of said sear provided with a triangular-like cam portion, a transverse cylindrical sear slide slidably mounted in a bore in the bolt, said sear slide having an actuating end portion extendable from the bolt and being reversibly mounted for slidable movement in said bore responsive to an outside force from either side of the bolt, spring means for resiliently projecting said actuating end portion from the bolt, said sear slide being provided with a recess for receiving said cam portion, a pair of angularly related chordal portions having spaced-apart inclining walls in said recess, said chordal portions being selectively cooperable with said cam portion for pivoting said sear to unlatch said firing member when said sear slide is mounted for actuation from either side of the bolt, a lug on said sear cooperable with said sear slide for blocking said sear against movement away from latching cooperation with said firing member when said sear slide is in normal position and to be receivable by a mortise in said sear slide when said cam portion is in cooperating engagement with one of said inclining walls for pivoting said sear to unlatch said firing member and said actuating end portion is moved against said spring means, and an actuator member slidably mounted in a cylindrical hole in the bolt, said actuator being slidably received by one of a pair of holes through said sear slide for securing said sear slide against rotation when mounted for actuation from either side of the bolt and for camming cooperation with said sear slide to actuate said sear slide from the top side of the bolt.
